UNITED STATES PATENT OFFICE

2,097,673

TEXTILE MACHINE

Robert W. McLean, Bridgewater, Mass., assignor
to Carver Cotton Gin Company, East Bridge-
water, Mass., a corporation of Massachusetts

Application December 31, 1935, Serial No. 56,845

5 Claims. (Cl. 19—62)

This invention pertains to textile machines designed to remove useful fiber from its attachment and in particular to machines of the general class termed "gins" wherein toothed disks or "saws" 5 projecting through slots between parallel bars of a "grate-fall" constitute the instrumentalities for removing the fiber,—for example, for detaching cotton fiber from the seeds.

Commonly, the grate-fall comprises a series of independent bars secured in assembled relation by attaching them individually at their upper and lower ends to a pair of transversely extending rails. Such a construction is illustrated in the patent to McLean No. 1,999,845, dated April 15 30, 1935, wherein mention is made of some of the difficulties frequently encountered in building an acceptable grate-fall, and wherein an improved construction is disclosed such that some of these prior difficulties are overcome. In the copending 20 application for Letters Patent filed May 10, 1935, Serial No. 20,952, by Robert W. McLean, there is described a further improvement designed primarily to prevent "tagging", that is to say, the formation of loosely coherent masses of fiber or 25 dirt in the space behind the grate-fall and just above the ginning point. With that object, among others in view, said application describes various improved grate-fall constructions, one of them having the slots cut in a continuous piece 30 of sheet metal. Such an integral grate-fall construction has certain advantages, among them accurate parallelism of the slots, as compared with constructions in which independent bars are individually attached by means of screws or the 35 like to top and bottom rails. However, as a practical matter, it has been found almost impossible to harden the bars (that is to say, the metal intervening between the slots) of such integral grate-fall at points adjacent to the ginning point so 40 that they will effectually resist wear, without distorting the sheet material and thus throwing the slots out of parallel. While such integral grate-falls, having their bars unhardened, have been used, and while such grate-falls may make a 45 certain appeal to the user by reason of their cheapness, they wear so rapidly that the accuracy and efficiency of the gin is soon impaired.

Among the objects of the present invention are to provide a grate-fall of the tagless type (such 50 that tags or streamers do not readily form in the space above the ginning point); to provide a grate-fall which, throughout its life, maintains its slots in substantially the same accurately parallel relation that they have in the integral 55 type of grate-fall when first made; to provide a grate-fall whose bars may readily be hardened adjacent to the ginning point without distortion of the grate-fall as a whole; to provide a grate-fall having bars of sufficient depth to assure adequate rigidity and accuracy of the ginning opera- 60

tion as well as strength to resist the blows to which the grate-fall is often subjected either by saws which are out of true, or by the inclusion of stones or other hard bodies in the seed cotton; and to provide a grate-fall construction having 5 all of the above advantages but which may be made at a reasonable cost.

Other objects and advantages of the invention will be made manifest in the following more detailed description in which reference is made to 10 the accompanying drawings, wherein:

Fig. 1 is a vertical section showing an upper front portion of a gin, including the feed hopper, the roll box and saw cylinder, and also the improved grate-fall embodying the present invention; 15

Fig. 1a is a section on substantially the same plane as Fig. 1, but to larger scale, showing details of the upper part of the grate-fall;

Fig. 2 is a fragmentary front elevation of the 20 grate-fall, looking substantially in the direction of the arrow A (Fig. 1), certain parts being omitted or indicated in broken lines, and others broken away, and illustrative of appliances useful in mounting the grate-fall in the gin; 25

Fig. 3 is a fragmentary perspective view of the 20 upper part of the grate-fall and associated parts shown in Fig. 2;

Fig. 4 is a fragmentary elevation of the grate-fall, but illustrating a modified construction; 30

Fig. 5 is a fragmentary section, substantially on the line 5—5 of Fig. 4,—the central part of the grate bar being broken out;

Fig. 6 is a view similar to Fig. 5, but illustrating modified means for permanently securing the 35 upper end of the grate bar to the top rail;

Fig. 7 is a view similar to Fig. 5, but illustrating another mode of uniting the grate bars to the top and bottom rails;

Figs. 8 and 9 are views similar to Fig. 5, showing other modified constructions;

Fig. 10 is a section similar to that of Fig. 5, but showing the upper portion only of the grate-fall, illustrating another modification;

Figs. 11, 12 and 13 are views similar to Fig. 10, 45 but showing additional modifications; and

Fig. 14 is a transverse section, to larger scale, through one of the grate bars in a plane adjacent to the ginning point.

Referring to the drawings, the numeral 1 designates the feed hopper of a linter gin, such hopper having therein the ribbed feed roll 2 co-operating with the sliding gate 3 to deliver the seed at a proper rate to the roll box of the gin. The breast structure of the gin comprises the 55 breast board 4 which constitutes the forward wall of the roll box 5. This breast board carries the adjustable rake head 6 provided with the spaced teeth 7. The upper portion of the rear wall of the roll box is defined by the forwardly 60

concave liner plate 8 which may be of metal and which is fixedly secured at its opposite ends to the end members of the breast structure. Within the roll box 5 is arranged the float roll 9 which slowly turns the roll of seed cotton in the roll box so as to present it for engagement by the teeth of the saw cylinder.

The saw shaft 10 carries the saw cylinder 11 consisting of a series of spaced peripherally toothed saw disks which reach up through the slots in the grate-fall and tear the lint from the seeds and carry it down between the bars of the grate-fall. The doffer brush 12, having bristles 13, is arranged beneath the grate-fall in the usual manner to remove the lint from the saw teeth.

As here illustrated, the gin structure comprises the upper and lower elongate supporting strips or girders 15 and 16, here shown as of wood, and extending transversely across the entire width 20 of the gin structure. Preferably the lower rear corner of the upper strip or support 15 is rounded off or beveled, as indicated at B, so as to provide a clear space behind and above the ginning point, thereby contributing to the prevention of the 25 formation of tags or streamers behind the upper part of the grate-fall.

As here illustrated, the grate-fall comprises a series of parallel spaced grate bars 14 independently formed, preferably from sheet or bar steel 30 of suitable thickness and physical characteristics, the under edges of these bars preferably being beveled off, as indicated at 14a (Figs. 1 and 14) to provide clearance for the saw teeth as the latter pass between adjacent bars. Adjacent to 35 the ginning point G the bars are locally hardened, such hardened portions being indicated by stippling in the drawings. This local hardening may be accomplished by any suitable method of heat treatment, and after such hardening, the bars 40 may, if desired or necessary, be individually straightened and their edges and upper faces, if desired, may be ground and polished or otherwise finished to provide smooth and accurate surfaces. While ordinarily the bars will be of a 45 material, for example carbon steel, which by proper heat treatment may be hardened locally at the ginning point, it is contemplated that the bars might be of material not readily hardened by such methods, but which be surface hardened, 50 at least, at the ginning point, for example by nitriding, chromium plating, case hardening, or the like, it being noted that by making the bars as individual elements, such modes of hardening are applicable whereas, were the bars to be made 55 by slotting a single sheet of material, such local hardening would not be practical.

As illustrated in Fig. 1, the bars 14 are united at their upper and lower ends respectively to rail members 17 and 18 respectively, such rail members 60 being of metal and being disposed parallel to each other. As shown in Figs. 1 and 1a, the upper ends of the bars 14 are abutted against the upper rail 17, with the upper forward corner 19 of the bar substantially in contact with the 65 rail 17, thus leaving a wedge-like space between the lower edge of the rail 17 and the upper end surface of the bar. This wedge-shaped space is then filled with welding metal 20 which permanently and securely unites the bar to the rail. 70 This weld may be made by any of the well-known methods, such as arc-welding, acetylene-welding, or the like, and it is even contemplated that, if the materials of the bars 14 and the rail 17 are suitable, the joint may be made by brazing. 75 Whatever method be employed, the ultimate re-

sult, as above stated, is to form a permanent union between the bar and the rail so that when once thus joined, there can be no possibility of displacement of one bar with respect to adjacent bars.

As illustrated in Fig. 1, the lower end of the bar 14 is preferably beveled, as indicated at 21, and placed in juxtaposition to the upper edge surface of the lower rail 18. In the wedge-like recess between the surface 21 and the edge of 10 the rail, welding metal 22 is introduced, the weld being made in accordance with any of the methods above described so as permanently to unite the lower end of the bar to the rail. It will be understood that in thus welding the several bars 15 to the top and bottom rails, any suitable appliances may be used for holding the bars in accurately spaced parallel relation while they are being welded.

For securing the grate-fall in place in the 20 gin, it is preferred to provide the top and bottom rails 17 and 18, respectively, with a series of holes 23 and 24, respectively (Fig. 2), for the reception of screws 25 or equivalent fastening means 25 designed to enter the usual supporting strips 15 and 16, respectively and thus hold the grate-fall in operative position. The strips 15 and 16 are sometimes of wood and sometimes of metal, and appropriate fastening means will be used in accordance with the character of the strip, the 30 strips being herein illustrated, for convenience, as of wood and the fasteners shown are wood screws.

Preferably, in view of the fact that gins of substantial width are now commonly employed, and 35 that the grate-fall is thus of considerable length and difficult to ship as a single unit, it is preferred, in accordance with the present invention to divide the grate-fall into several sections. For this purpose the rails 17 and 18 each consists (Fig. 40 2) of a plurality of substantially like sections. Each corresponding pair of rail members carries a series of the grate bars 14, the latter, as above noted, being permanently and fixedly united to the rail section so as to form a unitary and permanent structure in which the widths of the slots 45 may be accurately fixed by the manufacturer. By thus making the grate-fall in several sections, difficulties in manufacture are avoided, and the replacement or repair of a broken or bent 50 bar is facilitated.

In order to ensure the proper mounting of the sections of the grate-fall upon the supporting strips 15 and 16 of the gin, it is preferred to furnish a pair of stiff aligning bars to accompany 55 each grate-fall when the latter is shipped to the user. Such a pair of aligning bars is indicated at 28 and 29 (Figs. 2 and 3), each bar being provided with a series of properly spaced holes 30 large enough to permit the free passage of the 60 heads of the screws 25 by means of which the rails 17 and 18 are mounted in the gin. The aligning members 28 and 29 are also furnished at intervals with unthreaded holes for the passage of bolts 32, while the rails 17 and 18 are furnished 65 with threaded openings to receive the threaded portions of these bolts. The holes in the aligning bars 28 and 29 and the corresponding holes in the several sections of rails 17 and 18 are drilled by the manufacturer in such a way as to be in accurate alignment when the several sections of the grate-fall are in proper operative relation.

When the user of the grate-fall is ready to mount the grate-fall in the gin, he assembles 70 the sections in substantial alignment and then 75

lays the aligner bars 28 and 29 upon the top and bottom rail members of the several sections, securing them in place by means of the bolts 32. When the parts are thus united by means of the aligner bars, the user is assured that the several sections are in proper operative relation. He then mounts the entire grate-fall in the gin, passing the attaching screws 25 through the large openings 30 and 31 in the aligner bars and screwing them into the top and bottom strips 15 and 16 of the gin structure. When all of the attaching screws have thus been inserted, the bolts 32 are taken out and the aligner members 28 and 29 removed, thus leaving the grate-fall properly mounted in the gin.

The several bars 14 of the grate-fall preferably are provided with notches in their upper surfaces closely adjacent to the ginning point G, and after the several sections of the grate-fall have been secured to the upper and lower rails, a guard or wear plate 26 (Fig. 1a) is arranged to overlap the upper rail 17 and to cover the junction of such rail with the upper ends of the bars. This guard plate has its lower edge 27 (Fig. 1a) seated in the aforesaid notches in the upper faces of the several bars, its lower edge extending continuously across the bars and across the slots between the bars and in effect defining the upper ends of the slots. This edge 27 is very closely adjacent to the ginning point G (Fig. 1); for example, it may be spaced from such point a distance of the order of one-eighth inch so that the teeth of the saws of the saw-cylinder pass so close to such edge that they continuously sweep out the end of the slot and thus prevent the accumulation of lint and the formation of tags or streamers just above the ginning point. The guard or wear plate 26 is furnished with openings for the passage of screws 25a (Fig. 1a) which attach the plate to the top rail 17. The upper edge of the guard plate 26 substantially abuts the lower edge of the rear wall 8 of the roll box and in effect forms the lower part of such wall.

While the method of permanently uniting the grate bars to the top and bottom rails, as above described, is desirable, I contemplate the employment of other and equivalent constructions, some of which have herein been illustrated by way of further example. Thus in Figs. 4 and 5, the upper rail comprises a metal plate 15a which projects forwardly beyond the front face of the wood strip 15 and its forward edge has a series of regularly spaced notches 33 (Fig. 4), each of a width to receive the upper end of one of the bars 14 with a snug fit, and spaced from the next notch a distance equal to the desired width of the slot between the bars of the grate-fall. In this construction the lower rail member 18x (Fig. 4) is furnished with a similar series of notches 34 in its upper edge, the notches 33 of the member 15a being in alignment with the notches 34.

As illustrated in Fig. 5, a member 17a is secured to the front face of the strip 15 with its lower edge in contact with the forwardly projecting notched part of the member 15a. The grate bars 14a are beveled at their upper ends above ginning point G and these beveled ends are fitted into the notches 33 and are permanently secured to the members 15a and 17a by a body 35 of welding metal. This metal may extend continuously across the width of the section of the grate-fall or may be in the form of individual masses each uniting one of the bars only to the members 15a and 17a. This weld may be made in any of the ways above suggested and permanently unites the bar to the top rail struc-

ture. As illustrated, a guard plate 26 is arranged to fit against the front face of the rail member 17a and to have its lower edge seated against a shoulder at the lower end of the bevel of the grate bar. As shown in Fig. 5, the lower end of each grate bar 14a is seated in one of the notches 34, the bar being of greater depth than the thickness of the rail 18x, and a body of welding metal unites the upper part of the lower end of each bar to the upper face of the rail 18x.

In Fig. 6 a further modification is illustrated wherein the upper rail member 17b is secured to the strip 15 by screws and has a forwardly directed horizontal flange 37 provided with notches 15 in its forward edge for the reception of the upper ends of the grate bars 14. A wedge or spacer block 38 is attached to the front face of the rail 17b with its lower edge spaced from the flange 37. The upper ends of the bars 14 are disposed, one in each of the notches in the flange 37, and then a body of welding metal 39 is flowed into the space between the flange 37 and the lower edge of the block 38, thus permanently and firmly uniting the several bars to the rail member 25 17b. A guard plate 26, similar to that above described, is mounted to rest against the front face of the block 38 and against the front edge of the flange 37, with its lower edge against shoulders near the upper ends of the bars 14 adjacent to 30 the ginning point. As illustrated in Fig. 6, the lower ends of the bars 14 are secured to the lower rail 18x in the same way as illustrated in Fig. 5.

As shown in Fig. 7, the top rail includes the member 17c to which is secured a part 40 whose lower margin is deflected downwardly and forwardly, as shown at 41. The upper ends of the bars 14 are rabbeted to provide recesses of a depth substantially equaling the thickness of the part 41, and the lower edge of the member 41 is seated in these recesses and the parts are joined together by spot welding, as indicated at 43. In this instance the member 40 not only permanently unites the several bars 14, but also forms the guard plate, its lower edge closing the slots between the bars and defining the upper ends of the slots. At their lower ends 44 the bars 14 are rabbeted at their under sides and fit over the upper margin of the lower rail member 18m to which they are secured by spot welding at 45.

As shown in Fig. 8, the strip 15 supports a top rail member 17e whose forward surface 51 is beveled and constitutes the effective lower portion of the roll box wall 8. The lower edge of the rail 17e is inclined so as to intersect 55 the surface 51 at an acute angle, and in this angle a series of notches is formed for the reception of the upper ends of the several grate bars 14. Preferably the inner ends of these notches are deeper than the bars and the latter are so arranged that their upper surfaces enter these notches substantially at the line of intersection of the front face 51 with the lower edge of the rail member. Above the upper edges of the bars 14, within the notches, bodies of welding material 53 60 permanently unite the bars to the rail 17e. The upper surfaces of these bodies of welding material are substantially flush with the surface 51. In this instance the metal of the rail 17e which separates the notches forms the terminus for the 70 slot between adjacent bars, the acute edge formed by the intersection of the surface 51 and the lower edge of the bar being very close to the ginning point G. The lower ends of the bars 14, as illustrated in Fig. 8, are united to the bottom 75

rail 18c by welding metal 36 in substantially the same way as illustrated in Fig. 5.

In Fig. 9 the top rail member 17d has the forwardly inclined flange portion 46 which forms a support for the upper ends of the bars 14. The bar is spot welded to the flange 46 at the point 47 so as permanently to unite it to the rail member. The upper ends of the bars 14 are reduced in thickness so as to provide a shoulder adjacent to the ginning point G and against this shoulder rests the lower edge of a guard plate 26a, preferably having a forward concave curvature providing a smooth continuation of the curved wall member 18 of the roll box. At its lower end 15 the bar 14 is cut away at its upper side so as to provide a tongue 48 which is received in an undercut notch 49 in the lower rail member 18d and a spot weld at 50 unites the parts 48 and 18d.

In Fig. 10 the top rail member 17f is shown as having a concavely curved forward surface 54 and a beveled lower edge provided with a shoulder. The upper end of the bar 14 is arranged to underlie this beveled lower edge of the rail 17f and welding material 55, interposed between the upper extremity of the bar and the shoulder, permanently secures the bar in place, it being noted that the curved surface 54 of the rail 17f forms a smooth continuation of the roll box wall 8 and merges smoothly with the upper edges of the bars 14 adjacent to the ginning point.

In Fig. 11 the top rail member 17g is shown as provided with a beveled lower edge to which the upper end of the bar 14 is secured by welding metal 20 in substantially the same way as illustrated in Fig. 1a. However, in this instance the guard plate 55 is of forwardly concave curvature, forming a smooth continuation of the wall member 8.

Fig. 12 illustrates an arrangement wherein the horizontal top rail 17m has spaced integral projections 56 at proper intervals which enter holes in the upper ends of the respective bars 14, the forward ends of the members 56 being riveted over in the forward parts 57 of these holes so as permanently to unite the bars to the member 17m.

In Fig. 13 a further modification is shown wherein the wood strip 15 carries the forwardly concave combined guard plate and top rail 26s, beneath whose lower edge the upper ends of the bars 14 are disposed and to which the bars are permanently united by rivets 58.

While various embodiments of the invention have been illustrated by way of example, it is to be understood that the constructions shown are to be regarded merely as instances of practical embodiments of the invention and are not to be considered as limiting the scope thereof, and that all other equivalent constructions falling within the scope of the appended claims are to be regarded as within the purview of the invention.

I claim:

1. A grate-fall comprising a unitary structure including parallel top and bottom rail members, the top rail member having a series of regularly spaced recesses at its lower portion and the bottom rail member having a similar series of recesses adjacent to its upper edge, a series of parallel, spaced bars, the upper and lower ends of each bar fitting within aligned recesses in the top and bottom rail members, respectively, and a body of metal permanently uniting the ends of each bar to the top and bottom rail members, respectively, the recesses in the top rail member being deeper than the bars and the body of metal

which unites each bar to the top rail filling the recess above the bar flush with the forward face of the top rail member.

2. A grate-fall comprising a unitary structure including parallel top and bottom rail members, the lower edge surface and the forward face of the top rail member being acutely convergent and intersecting in a line closely adjacent to the ginning point, said rail member having a series of regularly spaced notches extending inwardly from said line of intersection of its lower edge surface and top face, a series of parallel, spaced bars, the upper end of each bar being disposed in one of the notches of the top rail member, the upper edge of said bar entering its notch substantially at the line of intersection of the front and bottom surfaces of the top rail member, welding material filling each such notch above the bar and permanently uniting the bar to the top rail member, the upper surface of said welding metal being flush with the top surface of the top rail member, and means uniting each bar to the lower rail member.

3. A grate-fall comprising a unitary structure including parallel top and bottom rails, the top rail comprising a sheet metal plate having an outstanding flange provided with a series of regularly spaced notches, a filler block secured to the plate but spaced from said flange, a series of parallel grate bars each having a recess in its upper edge closely adjacent to the ginning point, the upper end of each bar being disposed in one of the notches in the flange of the plate, welding metal disposed in the space between the flange and the filler block and permanently uniting the several bars to the plate, a guard plate resting upon the filler block and upon the edge of the flange and having its lower edge seated in the recesses in the several bars, and means permanently uniting the lower ends of the bars to the bottom rail.

4. A grate-fall for gins comprising a plurality of sections, each section comprising parallel top and bottom rail members and a plurality of independent grate bars each permanently welded at its upper and lower ends, respectively, to the top and bottom rail members of its particular section, alignment bars disposed to extend from end to end of the grate-fall in contact with the upper and lower rail members of the several sections, respectively, said aligning bars and rail members, respectively, having openings which register when the several sections are in properly aligned operative relation, and removable fastener means passing through said openings and temporarily clamping the sections to the aligning bars.

5. A grate-fall comprising a unitary structure including parallel top and bottom rail members, a plurality of spaced, parallel independent bars, the upper and lower ends of each bar abutting the top and bottom rail members, respectively, each bar being locally hardened adjacent to the ginning point and having a recess in its upper face adjacent to the ginning point, welding metal permanently and rigidly uniting each bar at its upper and lower ends, respectively, to the respective rail members, and a guard plate overlapping the junction of the bars with the upper rail and having its lower edge seated in the recesses of the several bars, said lower edge of the guard plate extending uninterruptedly from one bar to the next closely adjacent to the ginning point.
